Primary Examiner — Terry Wallace(74) *Attorney, Agent, or Firm* — Lowe Graham Jones PLLC(57) **CLAIM**

I claim the ornamental design for the collapsible produce keeper, as shown.

DESCRIPTION

FIG. 1 is a perspective view of the collapsible produce keeper, showing my new design;

FIG. 2 is a front view of the collapsible produce keeper;

FIG. 3 is a top view of the collapsible produce keeper;

FIG. 4 is a right side view of the collapsible produce keeper;

FIG. 5 is a left side view of the collapsible produce keeper;

FIG. 6 is a back view of the collapsible produce keeper; and,

FIG. 7 is a bottom view of the collapsible produce keeper.
